UNITED STATES PATENT OFFICE

STONE HALLQUIST, OF MILWAUKEE, WISCONSIN, ASSIGNOR TO S. M. SIESEL CO., OF MILWAUKEE, WISCONSIN, A CORPORATION OF WISCONSIN

MOLD CONSTRUCTION FOR PILING

Application filed February 8, 1932. Serial No. 591,506.

This invention relates to improvements in molds for the horizontal casting of piles of cementitious material, and more particularly to an improved form of securing clamp for the molds.

In co-pending application Serial Number 574,432, filed November 6th, 1931, there is disclosed a horizontal mold in which is disposed a reenforcement for the cement pile or column cast therein, the mold being secured in assembled condition by a plurality of mold encircling clamps. In said prior mold construction curved side plates were in detachable engagement with a curved bottom plate and in order to maintain the curved side plates in proper relationship the upper portion of the reenforcement carried chairs to space the upper portions of the mold plates from the reenforcement and to hold the same against the inner surfaces of the clamps. Under certain conditions it was found that the strains and stresses imposed by cementitious material within the mold reacted against said side plates of the mold to bow the same somewhat, and the present invention, therefore, constitutes an improvement over the invention of said copending application insofar as the clamps are concerned and means employed in connection therewith for maintaining the side plates of the mold in proper relationship to the other mold parts under all conditions.

A further object of the invention is to provide clamps for circular sectional molds formed with simple means for engaging the upper edges of the curved side plates of the mold whereby pressure exerted on said side plates by material within the mold will force the plates against said engaging means and also against the mold bottom plate insuring proper disposition of the mold side plates and preventing distortion thereof.

A further object of the invention is to provide a mold clamp construction which will eliminate the need of mold section maintaining chairs on the upper portion of inner reenforcement.

A further object of the invention is to provide a mold construction of the class described which is more simple, inexpensive

and efficient than the mold construction disclosed in said copending application.

A further object of the invention is to provide a circular mold construction for horizontally cast piling which is strong and durable, is easily manipulated, assembled and disassembled, and is well adapted for the purposes set forth.

With the above and other objects in view the invention consists of the improved mold construction, and its parts and combinations as set forth in the claims, and all equivalents thereof.

Novel features disclosed but not specifically claimed herein form the subject matter of said copending application Serial Number 573,432, filed November 6th, 1931.

In the accompanying drawing in which the same reference characters indicate the same parts in all of the views.

Fig. 1 is a side view of the improved mold construction with parts broken away and in section to show details of construction;

Fig. 2 is an enlarged cross-sectional view of the mold construction;

Fig. 3 is an enlarged fragmentary plan view of the mold construction; and

Fig. 4 is an enlarged fragmentary side elevation.

Referring now more particularly to the drawing it will appear that the numerals 6 indicate a plurality of transversely disposed supporting timbers positioned upon the ground or other desired surface and said timbers 6 support an elongated base plate 7 which is arcuate in cross-section. In order to maintain the plate 7 in desired position upon the supporting timbers against lateral or rocking movement wedge members 8 are utilized which engage surface portions of the base plate 7.

The outer face of the base plate 7 at predetermined points spaced lengthwise thereof and at opposite sides of its transverse center is provided with laterally disposed clips 9. Said clips are positioned relatively close to the longitudinal marginal portions of the plate 7 but are arranged inwardly thereof and said clips have their outer or receiving ends disposed toward the longitudinal edges

of the plate 7. Said outer or receiving end portions of the clips 9 are disposed at an angle away from the plate 7 thereby facilitating the proper and ready engagement therewith of the inner longitudinal edge portions of curved side plates 10. The curved side plates 10 are each of a length substantially co-extensive in length with the base plate 7 and possess sufficient inherent resiliency to allow themselves to be transversely flexed to conform to the interior curvatures of arcuate clamping members 11 secured therearound.

The curved base plate 7 is also adapted to transversely flex somewhat to accommodate itself to the clamping members 11 and the inherent resiliency or flexibility of the plates 7 and 10 permits said plates to be employed in the production of piling or kindred columns of varying diameters as determined by the size of the clamping members 11 employed in connection therewith. The curved side plates 10 are of such transverse dimensions to assure the upper marginal edges thereof being spaced apart in the mold assembly to provide an upper opening 12 extending longitudinally of the mold thereby providing for effective pouring of the cementitious material into the mold assembly and also permitting such tamping as may be required.

The clamping members 11 as herein disclosed are arranged in pairs with the members 11 of each pair pivotally connected, as at 13. The opposite or free end portion of one of the members 11 is provided with a hook member or catch 14 which is adapted to engage with a loop member 15 which is pivotally connected with a lever 16 inwardly of an end of the lever. Said end portion of the lever is pivotally connected with the free end portion of the other clamping member 11, as at 17, so that upon proper pivotal movements of said lever, with the loop 15 engaged with the hook 14, the pair of clamping members 11 may be brought into proper holding arrangement around the mold assembly. The clamping members 11 are disposed with respect to the horizontal mold assembly so that the pivotal connections 13 are on one side of the mold coincident with the horizontal plane of the axis of the mold, while the loops and levers are directly opposite on the other side of the mold.

The clamping members 11 are provided with relatively broad contacting surfaces 19 with which the plates 10 directly engage. Each clamp (consisting of two joined clamping members 11), as thus disposed, is formed on the inner surface of the upper portion of a contacting surface with a pair of spaced-apart transverse bosses 18, said bosses being formed by short rod sections welded to the inner face of the contacting surface 19 and having weld material on outer sides thereof, as at 20, for reinforcing and strengthening

purposes. These bosses 18 of each clamp are spaced equi-distant from the vertical plane of the axes of the mold sufficiently far to be engaged by or in abutment with the upper marginal edges of the side plates 10. When the 70 clamps are secured in position, as previously described, the side plates will be engaged between the bosses 18 and the clips 9 of the base plate, and the force exerted by the clamps and the inherent resiliency of the side plates 10, being confined between the members 18 and 9, will assure contact of the plates with the contacting surfaces 19 of the clamps, assuring the desired cross-sectional configuration of the piling produced within the mold, 80 and preventing distortion of the mold from pressure of material therewithin.

Before the cementitious material is applied within the mold assembly there is properly positioned within the assembly a reinforcement 21 comprising a plurality of spaced elongated bars 22 of a required length about which a wire 23 of a suitable gauge is wound spirally and is secured to the rods by welding at the points of juncture. The reinforcement 21 is disposed within the mold assembly on beam chairs 24 connected in pairs by arcuate plates 25, said supports being positioned where desired on the base plate 7. Said supports assure the desired maintenance of the reinforcement within the mold assembly with a resultant desired embedment of the reinforcement within the completed cast piling. Due to the engagement of the upper marginal edges of the mold side plates 10 said side 100 plates are maintained in proper spaced relationship to the peripheral portions of the reinforcement.

The ends of the mold assembly, prior to the pouring of the cementitious material, are closed respectively by end closure members positioned within the respective ends of the mold assembly as shown and described in co-pending application Serial No. 573,432, filed November 6th, 1931.

It is evident that after a piling has been molded and the material has set sufficiently, the clamps 11 may be released which will cause a disengagement between said clamps and the side plates 10. Said side plates may then be removed and the finished piling may be rolled laterally from the base plate 7 free of the mold.

From the foregoing description it will be seen that the improved mold construction for the horizontal casting of piling is simple and permits convenient and expeditious casting of piling. The improved clamp arrangement results in a simplified construction as it eliminates the need of spacing means between the inner reinforcement and the side plates of the mold, and it further insures correct disposition of said side plates without distortion during molding operations. It should be understood that it is not desired to limit the invention to the exact details of construction 130

herein shown and described, inasmuch as various modifications within the scope of the claims may occur to persons skilled in the art.

What is claimed as the invention is:

- 5 1. A mold assembly, comprising a central elongated horizontally disposed plate, engaging means carried thereby, resilient side plates having their lower longitudinal marginal portions coacting with said engaging means, clamps adapted to releasably encircle the assembly and to flex said side plates, and means on the inner faces of said clamps engaging the upper longitudinal marginal portions of said plates to 10 confine said plates under pressure and in flexed condition between said means and said engaging means to provide a molding chamber.

- 15 2. A mold assembly, comprising a central elongated horizontally disposed plate, engaging means carried thereby, resilient side plates having their lower longitudinal marginal portions coacting with said engaging means, clamps adapted to releasably encircle the assembly and to flex said side plates, and means on the inner faces of said clamps engaging the upper longitudinal marginal portions of said plates to hold said plates against the clamps and to releasably confine said 20 plates under pressure and in flexed condition between said means and said engaging means to provide a molding chamber, the upper longitudinal marginal portions of said side plates being spaced apart to provide 25 a filling opening.

- 30 3. A mold assembly, comprising a central elongated horizontally disposed plate, clips carried thereby, resilient side plates having their lower marginal portions detachably engaged by said clips, clamps adapted to releasably encircle the assembly and to flex said side plates, and spaced bosses formed transversely on the upper inner surfaces of the clamps against which the upper longitudinal margins of said side plates abut whereby said side plates are releasably confined under pressure and in flexed condition 35

between said clips and bosses and against the inner surfaces of the clamps to provide a molding chamber, the upper longitudinal marginal portions of said side plates being spaced apart to provide a filling opening. 70

4. A clamp for circular sectioned molds, comprising a pair of curved, pivotally connected arms, the inner surfaces of said arms having relatively broad and flat contacting faces, a pair of spaced bosses secured transversely to the contacting face of one arm, and complementary securing means formed on the free ends of said arms. 75

5. A mold assembly, comprising a central elongated, horizontally disposed plate 80 having side plate engaging means thereon, a curved clamping member having a pair of spaced abutments thereon, and a pair of resilient side plates, the lower longitudinal edge portions of said side plates being engaged with said plate engaging means, said side plates being adapted to be distorted to the curvature of the clamping member, the upper longitudinal edges of said side plates engaging said abutments and 85 said plates being confined between said plate engaging means and the abutments and being distorted to the curvature of the clamping member by end pressure applied to said plates by said abutments. 90

6. A mold assembly, comprising a central elongated, horizontally disposed plate having side plate engaging means thereon, a curved clamping member having a pair of spaced abutments thereon, and a pair of resilient side plates, the lower longitudinal edge portions of said side plates being engaged with said plate engaging means and the upper edges of said plates being engaged with said abutments in a manner so that said plates are confined between the abutments and plate engaging means and distorted to the curvature of the clamping member by end pressure applied to the plates by the abutments in the direction of the plate engaging 100 means. 105
